Primary Examiner — David G Muller*Assistant Examiner* — Nathan M Johnston*(74) Attorney, Agent, or Firm* — Lathrop Gage LLP(57) **CLAIM**

We claim the ornamental design for sampling device, as shown and described.

DESCRIPTION

FIG. 1 is an upwardly side perspective view of sampling device showing our new design.

FIG. 2 is a rear elevation view thereof.

FIG. 3 is a downward perspective view thereof; and,

FIG. 4 is a front elevation view thereof.

The broken lines show portions of the design that form no part of the claimed design.
